United States Patent [19]

Nava et al.

[11] Des. 252,069

[45]  Jun. 12, 1979

[54] DOUBLE BLOCK FOR BOATS

[75] Inventors: Riccardo Nava; Alessandro Ubertazzi; Riccardo Soffientini; Giorgio Romani, all of Milan, Italy

[73] Assignee: Nemo S.p.A. of Zona Industriale, Sarsina, Italy

[] Term: 14 Years

[21] Appl. No.: 786,324

[22] Filed: Apr. 11, 1977

[30] Foreign Application Priority Data

Oct. 15, 1976 [IT] Italy 14753 A/76

[51] Int. Cl. D12—05

[52] U.S. Cl. D8/360

[58] Field of Search D8/360, 358; 254/192, 254/189, 188

[56] References Cited

U.S. PATENT DOCUMENTS

10,688	3/1854	Webber	D8/360 X
D. 240,895	8/1976	Werner	D8/360
1,771,484	7/1930	Byers	254/192
3,179,376	4/1965	Botten	254/188 X
3,733,053	5/1973	Haulotte	254/192

Primary Examiner—A. Hugo Word
Attorney, Agent, or Firm—Guido Modiano

[57] CLAIM

The ornamental design for a double block for boats, as shown.

DESCRIPTION

FIG. 1 is a side view of the double block for boats; FIG. 2 is a side view of the double block for boats, opposite to that shown in FIG. 1; FIG. 3 is a view from below of the double block for boats; FIG. 4 is a view from above of the double block for boats; FIG. 5 is a front view of the double block for boats.

Fig. 1

Fig. 2

Fig. 3

Fig. 5

Fig. 4